YARN CARRIER FOR KNITTING MACHINES

Josef Sylvester Karl, Athens, Ga.

Application July 7, 1949, Serial No. 103,346

5 Claims. (Cl. 66—126)

1.

My invention relates particularly to carriers which run back and forth to deliver yarn or thread to the knitting mechanism as in the manufacture of full-fashioned hosiery. Such devices usually have one or more introductory or receiving guides which receive the yarn from the conditioning chamber and a guide tube which delivers the yarn to the sinkers and dividers. These guides are subjected to wear by the yarn which frequently results in cutting and breaking of the yarn and a consequent shut down of the machine for repair or replacement of the damaged part and rethreading the carrier. As these machines have many sections the loss in production during a shut down is multiplied.

Provision has already been made for conveniently removing and replacing the delivery tubes but so far as I know no simple, practical, accessible and satisfactory means has heretofore been devised for removing and replacing adequate introductory guides without disturbing the connection and adjustment of the carrier. These carriers should be so constructed as to facilitate replacement and rethreading of the yarn and present a minimum frictional resistance to the travel of the yarn.

I have accordingly provided such introductory guides which are readily and quickly attachable and removable without disturbing the adjustment of the carriers.

Fig. 1 is a front view showing one form of attachment of my invention applied to a conventional carrier and rod.

Fig. 2 is an edge view of the same, the rod being shown in cross-section.

Fig. 3 is an enlarged cross-sectional view taken on the plane of the line 3—3 of Fig. 1.

Fig. 4 is an enlarged cross-sectional view taken on the plane of the line 4—4 of Fig. 1.

Fig. 5 is an exploded front view showing a modified form of attachment.

Fig. 6 is an enlarged cross-sectional view taken on the plane of the line 6—6 of Fig. 5.

Fig. 7 is an enlarged cross-sectional view taken on the plane of the line 7—7 of Fig. 5.

Fig. 8 is a perspective view of another modified form of attachment.

Fig. 9 is an enlarged cross-sectional view taken on the plane of the line 9—9 of Fig. 8.

Fig. 10 is a perspective view of a fragment of a detachable bracket showing a simplified form of yarn guide at its upper end.

The carrier assembly consists of a holder plate 10 and a depending arm 11. The holder plate is secured to the carrier rod 12 by screws 13, 13 and

has slots 14, 14 to allow for the screws 15, 15 which are seated in the upper end of the arm 11. A strap 16 serves as a clamp by which the arm is adjustably secured to the holder plate.

5 In Figs. 1 and 2 I have shown introductory guides 17, 18 and 19 in the form of vertically spaced eyelets located in the general positions of the guides commonly provided in such carriers. These guides are carried by a bracket 20 which is detachably connected to the holder plate of the carrier assembly. This bracket has a cross-piece 21 with a hook 22 at one end engaging one edge of the plate 10 and a resilient latch member 23 at the other end adapted to be snapped over the opposite edge of the holder plate. This latch 23 has a finger piece by which it may be engaged for detachment of the bracket with all of the guides 17, 18 and 19. The vertical portion of the bracket may be bent to conform with the 10 angular bend in the carrier assembly which exists in many such devices. The cross-piece 21 of the bracket may be adjusted up and down on the holder plate above the clamp 16.

The eyelet guides may be formed of any suitable material which is hard, smooth and non-corrosive, such as glass, porcelain, carboloy or stainless steel and each may be removable. For instance, an eyelet may be detachably held to the bracket by a strap 25 which encircles the eyelet and slidably embraces the edges of the vertical portion of the bracket as shown in Fig. 4. The eyelets may also be freely rotatable so as to reduce the friction, distribute the wear of the yarn and prolong the life of the guides.

30 The outlet or delivery tube 26 is supported at the lower end of arm 11 and may be detachably secured in place in any desired manner.

35 In the form shown in Fig. 5, the holder plate 10' is extended upwardly beyond the holes 13' through which the screws 13 (of Fig. 1) pass to connect to the carrier rod. The bracket 20' has spaced guides 17', 18', 19' and 19''. In this case each guide is in the form of an eyelet held 40 rotatingly but securely in place by a pin 27 which passes through ears 28 bent up from the edges of the bracket 20' and across the peripheral groove in the eyelet. The bracket may be extended down the arm 11' to support a guide 19'' at a point above the discharge tube and the bracket may have cross pieces 21' and 29 similar 45 to cross-piece 21 for snap-on engagement with plate 10' and arm 11', respectively.

50 Figs. 8 and 9 show a supporting bracket 20'' with three spaced guides 17'', 18'' and 19'' and a pair of ears 19^b for the mounting of a fourth

guide (not shown). Each of these guides consists of a hardened roller or tube 30 rotatably supported in or between ears 31 at the edges of the bracket 20". Such a tube 30 is preferably supported on a pin or pins 32. In this case the yarn is guided beneath the successive rollers to the discharge or delivery tube such as 26 in Figs. 1 and 2. A solid hardened pin may be used in place of a tube.

Instead of the eyelet guides of Figs. 1 to 7 or the roller guides of Figs. 8 and 9 the detachable bracket 35 may have yarn guides formed by bending up lugs such as shown at 36 at the upper end of the bracket in Fig. 10 and providing a smooth edged hole 37 as the guide-way for the yarn. In case the guide-way becomes worn it is a simple matter to detach the bracket and replace it with one in which the guides are all in good order.

The top guide where there is the greatest lateral swing of the yarn as the carrier moves back and forth may be formed as shown in Figs. 1 to 7 or in Fig. 10. Some of the guides on a given bracket may be of one form and the others of another form. In any case all of the guideways, other than the discharge or delivery guide 26, will be removable and replaceable with the bracket.

It should be understood that the bracket will be constructed so as to locate the guides at the proper positions depending upon the positions in which the carrier must be used.

If anything goes wrong with one of the introductory guides, it is only necessary to detach the bracket and replace it with a perfect bracket which requires only a few seconds and does not require any readjustment of the carrier assembly. The troublesome bracket with its guides may then be repaired or discarded. These features are especially important when it is considered that there is very little room available in which to manipulate the parts. The guides being rotatable, very short and spaced apart naturally provide a minimum friction against the yarn. Such a construction is especially important when nylon yarn is used in such a machine as nylon yarn is particularly destructive of guides.

I claim:

1. In a knitting machine, a carrier rod, a carrier assembly having a holder and an adjustable carrier arm, means including clamp screws for detachably securing said holder to the carrier rod, means for adjustably securing said arm to said holder, a bracket having introductory yarn guides spaced apart vertically along said bracket, means including a hook at one edge of said bracket and a manually operable latch at the opposite edge of said bracket for detachably connecting said bracket to said carrier assembly independently of the means for securing said holder

to said rod and without disturbing the adjustment of said arm and a yarn discharge tube at the lower end of said arm.

5 2. A carrier assembly for a knitting machine comprising a bracket having means including a hook for engaging one edge of a carrier assembly and a manually operable latch for engaging the opposite edge of the assembly for quickly and readily attaching it to such a carrier assembly and a plurality of short introductory yarn guides spaced vertically along the bracket and removable with the bracket without disturbing said assembly.

10 3. A carrier assembly comprising a holder plate for attachment at its upper end with a carrier rod, an arm having its upper end adjustably secured to the lower part of said plate and having a guide tube at its lower end, a bracket detachably secured to said plate, said bracket including a hook at one edge thereof and a manually operable latch at the other edge, a yarn guide carried by said bracket adjacent the upper end thereof, a yarn guide carried by said bracket at a lower part and a third yarn guide carried 15 by said bracket intermediate its ends.

20 4. A bracket for a carrier assembly having a snap-on means for attaching it to a carrier assembly, said means including a catch for engaging the carrier assembly and a latch for engaging an opposite part of said carrier assembly and having a plurality of guides carried by and removable with said bracket for guiding yarn over the assembly.

25 5. As an article of manufacture, a yarn carrier assembly for a knitting machine comprising a plate for attachment to a carrier rod, said plate having two spaced slots in its lower end, a carrier arm adjustably secured to said plate and a removable bracket having a cross bar and a longitudinal member, a yarn guide mounted on the upper and lower ends of said bracket, said cross bar having a hook on one end and a manually operable catch on the other end, said hook and catch member securing said bracket and its 30 40 45 yarn guides to said assembly without disturbing the adjustment of said yarn carrier on said plate.
